CLAIM

The ornamental design for the rustic torched wood beverage serving tray, as shown and described.

DESCRIPTION

This patent contains at least one drawing/photograph executed in color. Copies of this patent with colored drawing(s)/photograph(s) will be provided by the Office upon request and payment of the necessary fee.

FIG. 1 is a front perspective view of a rustic torched wood beverage serving tray, showing my new design.

FIG. 2 is a front elevational view of the invention.

FIG. 3 is a rear elevational view of the invention.

FIG. 4 is a right side elevational view of the invention.

FIG. 5 is a left side elevational view of the invention.

FIG. 6 is a top plan view of the invention; and,

FIG. 7 is a bottom plan view of the invention.
